UNITED STATES PATENT OFFICE

140,986

DESIGN FOR A BORING MACHINE

Otto E. Schurr, Hamilton, Ohio, assignor to General Machinery Corporation, Hamilton, Ohio, a corporation of Ohio

Application January 15, 1945, Serial No. 117,443

Term of patent 14 years

(Cl. D54—14)

To all whom it may concern:

Be it known that I, Otto E. Schurr, a citizen of the United States, residing at Hamilton, in the county of Butler and State of Ohio, have invented a new, original, and ornamental Design for a Boring Machine, of which the following is the specification, reference being had to the accompanying drawings, forming a part thereof: wherein

Figure 1 is a perspective view taken from the front and one side of a boring machine embodying my new design; and

Figure 2 is a perspective view taken from the rear and other side thereof.

I claim:

The ornamental design for a boring machine, substantially as shown.

OTTO E. SCHURR.
